UNITED STATES PATENT OFFICE.

FRANK L. G. CHAPMAN AND WILLIAM H. CHAPMAN, OF STEVENS POINT, WISCONSIN.

DESIGN FOR A BICYCLE-PROP LEG.

SPECIFICATION forming part of Design No. 33,921, dated January 15, 1901.

Application filed December 13, 1900. Serial No. 39,795. Term of patent 7 years.

To all whom it may concern:

Be it known that we, FRANK L. G. CHAPMAN and WILLIAM H. CHAPMAN, citizens of the United States, residing at Stevens Point, in the county of Portage and State of Wisconsin, have invented and produced a certain new and original Design for Bicycle-Prop Legs; and we do declare the following to be a full, clear, and exact description of the invention, such as will enable others skilled in the art to which it appertains to make and use the same.

The invention relates to a new and original design for a bicycle-prop leg; and it consists of a design of the shape and configuration shown in the accompanying drawings, in which—

Figure 1 is a perspective view of the design, and Fig. 2 is a bottom plan view.

The leading feature of the design comprises the straight body portion 1, having at one end a hole 2 and at the other end a transversely-disposed loop 3, the end of which terminates in a point 4, the loop being arranged to one side of a vertical line passed through the body portion.

What we claim is—

The design for a bicycle-prop leg as herein shown and described.

In testimony whereof we have hereunto set our hands in presence of two subscribing witnesses.

FRANK L. G. CHAPMAN.
WILLIAM H. CHAPMAN.
